UNITED STATES PATENT OFFICE.

FRANKLIN L. DAMRON AND LEROY DAMRON, OF LOS ANGELES, CALIFORNIA.

MEANS FOR UTILIZING WASTE GAS IN INTERNAL-COMBUSTION ENGINES.

1,283,096.

Specification of Letters Patent. Patented Oct. 29, 1918.

Application filed August 21, 1917. Serial No. 188,528.

To all whom it may concern:

Be it known that we, FRANKLIN L. DAMRON and LEROY DAMRON, citizens of the United States, residing at Los Angeles, in the county of Los Angeles and State of California, have invented certain new and useful Improvements in Means for Utilizing Waste Gas in Internal-Combustion Engines, of which the following is a specification.

- 10 Our invention relates broadly to internal combustion engines such as are employed in the operation of motor vehicles, and has for an object the provision of means for connecting the crank case of the engine with the carbureter or intake manifold for the purpose of saving such of the products of combustion as are generally discharged from the crank case, either through the oil intake or nozzle, or otherwise.
- 15 A considerable portion of the gases forming the products of combustion in the cylinders escape around the peripheries of the piston rings and are delivered therefrom to the crank case from which they are usually discharged or escape in some manner to the atmosphere. All types of motors are provided with a nozzle through which the oil is supplied to the crank case, and such gases usually escape through these nozzles. It is
- 20 an object, therefore, to provide means for establishing communication between the oil supply nozzle and the intake of the carbureter whereby the suction in the manifold may draw or induce a flow of the unburned gases from the engine to and for mixture with the fuel from the carbureter to the intake manifold.

Some engines have what is generally known as a "stove" by means of which air from the vicinity of the exhaust pipe of the engine is heated and induced in the intake manifold for facilitating the combustion of the fuel. With our device such means may or may not be used, but we prefer to dispense with the stove for the reason that the gas supplied from the crank, being hot, will serve the same purpose and afford better results than the hot air.

It is, however, necessary to supply air with the gas to the carbureter in order to increase the amount of oxygen above that which would be contained in the partially consumed gases, and for this purpose we provide an air valve in the means of communication between the engine crank case

and the carbureter, so that the same may be supplied with the gas in suitable quantities.

Other objects may appear as the description progresses.

We attain the objects of our invention by means of the elements disclosed in the accompanying drawings, in which: Figure 1 is a side elevation of a well known type of internal combustion engine as used for an equally well known type of automobile, in which our invention is shown applied to the engine and in readiness for use. Fig. 2 is a plan of our invention with the engine shown in broken lines in proximity thereto. Fig. 3 is a plan of a portion of the gas supply pipe and valve mounted therein. Fig. 4 is an elevation of the same, and Fig. 5 is a transverse section thereof. Similar characters of reference are employed in the several views of the drawings and throughout the specification for indicating the same or like parts.

In the type of engine shown, an oil supply nozzle 1, generally known as a "breather" is provided near the front end of the crank case 2. The carbureter 3 is connected by means of the intake manifold 4 with the engine cylinders 5, and a "stove" 6 is generally provided for attachment to the exhaust pipe 7 and the air intake 8 of the carbureter 3, the hot air from the vicinity of the exhaust pipe, as stated, being induced through pipe 9 leading from the stove to the carbureter, thence through the carbureter and into the cylinders.

In lieu of the pipe 9, we provide a tube 10, preferably of flexible character, which is suitably attached to the air intake 8 of the carbureter and is extended upwardly and forwardly of the carbureter to a point slightly to the rear of the "breather" 1. A rigid section of pipe 11, having a downwardly turned elbow 12 is attached removably to the opening in the breather nozzle at the end of the depending extension in lieu of the cap which is usually provided. The rear end of the pipe 11 is soldered or otherwise suitably connected with the forward end of the flexible tube 10, thus affording direct communication between the crank case 2 and the carbureter 3.

If for any reason, it should be desirable to use the stove 6 and pipe 9 in connection with the pipe 11 and tube 10, the rear end of the latter may be connected in a suitable manner with the pipe 9 instead of with the

105

110

carbureter, as shown. Such a combination is thought to be unnecessary, however, for we provide an air valve 13, as shown in Figs. 3, 4 and 5, which is slidably mounted 5 in a fitting attachable to the pipe 11, the valve seating in the lower extension 14 of the fitting and the stem 15 thereof being slidable in a boss 16 on the upper end of the body 17. The valve stem carries a collar 18 10 on the upper end and a spring 19 which is held in tension between the collar and the upper end of the body 17 of the fitting. A chamber 20 in the body 17 communicates 15 with the atmosphere by means of a plurality of apertures 21 in the top of the body and with the interior of the pipe 11 by means of a passage 22 terminating in a seat for the valve 13. A saddle 23 is integrally formed 20 with the valve body 17 and may be secured to the periphery of the pipe 11 by means of the rivets 24 shown, or otherwise, so as to render the connection air tight.

It will be apparent that the valve 13 and its stem will move downwardly with the 25 downward movement of the pistons, due to the vacuum created in pipe 11, thus compressing the spring 19 and permitting the entrance of a certain and necessary amount of air into pipe 11 for mixture with the gas 30 therein and for further mixture in the carbureter with the pure liquid fuel; the gas introduced through pipe 11 being heated, the air so introduced will also become heated before admission to the intake manifold and 35 the combustion of the fuel will be facilitated. This same effect, we are aware, is accomplished by the stove 6 and pipe 9, but the gas from the crank case is not supplied with the air as in our invention, and the means

disclosed for utilizing and burning all of 40 the waste gases from the engine provide greater economy in operation and a more perfect combustion than is possible in the well known form of device.

We do not desire to limit ourselves to the 45 exact form of the elements, or the particular combination shown and described, for it would appear to be possible to modify the structure shown substantially without enlarging the scope or departing from the 50 spirit of our invention, and we desire to claim broadly on the novel means and connections described.

Having thus described our invention, what we claim as new and desire to secure by 55 Letters Patent, is:

In combination with an internal combustion engine, and a carbureter connected therewith, a pipe having a rigid section attached to and communicating with the 60 breather opening to the crank case, a flexible section connecting said rigid section with said carbureter, and a valve mounted on said pipe having an air chamber open to the atmosphere and communicating with the interior of said pipe, said valve serving to normally close communication between said chamber and said pipe, and to open communication therebetween when a suction is 65 created in said pipe for drawing the unconsumed gases from the crank case into the 70 carbureter for further combustion.
